UNITED STATES PATENT OFFICE.

LOUIS STEIN, OF WASHINGTON, DISTRICT OF COLUMBIA.

CUSHION-HEEL.

1,360,811.

Specification of Letters Patent. Patented Nov. 30, 1920.

Application filed January 19, 1920. Serial No. 352,487.

To all whom it may concern:

Be it known that I, LOUIS STEIN, a citizen of the United States, residing at Washington, in the District of Columbia, have invented new and useful Improvements in Cushion-Heels, of which the following is a specification.

The object of my present invention is the provision of a cushion heel, formed of rubber or equivalent material, and embodying such a construction that it is possessed of good wearing quality, and is efficient in its cushioning action, and is adapted, by virtue of its calks and its suction provision, to take secure hold of the ground when it is new, and also after it has been worn to a considerable extent.

To the attainment of the foregoing, the invention consists in the improvement as hereinafter described, and definitely claimed.

In the accompanying drawings, hereby made a part hereof:

Figure 1 is an inverted plan of my novel rubber heel.

Fig. 2 is an elevation of one side of the same.

Fig. 3 is an elevation of the opposite side of the heel.

Fig. 4 is a detail section taken in the plane indicated by the line 4—4 of Fig. 1.

Fig. 5 is a detail section taken in the plane indicated by the line 5—5 of Fig. 1.

Fig. 6 is a plan of the heel.

Fig. 7 is a transverse central section of the same.

Similar numerals of reference designate corresponding parts in all of the views of the drawings.

My novel heel is formed of one piece of rubber, and is slightly concave at its upper side, the central portion of which is flat, so that when applied the top edges of the heel will bear solidly against the under side of a leather heel lift, as will also the central portion of the upper side. At the under side of its forward portion and at opposite sides of its longitudinal center, the heel is provided with two annular projections 1, the opening 2 in which is extended up into the body of the heel, so as to contribute to

the suction capacity of the projections 1, and at the same time admit of the heel being readily nailed to a shoe.

Disposed diagonally in the rear portion of the underside of the heel, and adjacent to one of the rear corners thereof, is an elongated suction chamber 3, and in rear of said chamber is a diagonal calk 4. In front of the chamber 3 is a comparatively long diagonal calk 5, which latter is recessed at 6 to facilitate the driving of nails through the apertures 7 in the recesses 6. The calk 5 is of a less depth than the calk 4, and it will be noticed in this connection that the projections 1 are preferably of a less depth than the calk 4.

The heel, characterized as stated, is molded or otherwise formed in one piece, of rubber or other equivalent material, and in use is opposed and nailed to a heel lift in the ordinary well known manner, and with quite as much facility as an ordinary rubber heel.

In the practical use of the heel, it will be apparent that the projections 1, by the suction they afford, will take secure hold of a pavement and prevent slipping. In this the projections 1 will be assisted by the rear calk 4, and the said projections 1 and the calk 4, will afford adequate cushioning means. In its gripping and cushioning action, the calk 4 will be materially assisted by the adjacent chamber 3, and after the calk 4 has become worn, it will be assisted in its gripping action and also in its cushioning action, by the calk 5. When the calks 4 and 5 as well as the projections 1 are worn to the body of the heel, it will be apparent that the heel will still be possessed of suction capacity by reason of the openings 2 extending up into the body of the heel and the chamber 3 that is originally formed in said under side. It will further be apparent that the chamber 3 between the calks 4 and 5 lends increased flexibility to the rear portion of the heel, and that the heel is possessed of triple suction—*i. e.*, includes three suction elements.

Notwithstanding the novel features and the practical advantages of my heel as set

forth, the heel is susceptible of being produced quite as cheaply as an ordinary rubber heel.

Having described my invention, what I claim and desire to secure by Letters-Patent, is:

A cushion heel concave and having a flat central portion at its upper side and also having at its underside a diagonal elongated recess adjacent to and spaced from one rear

corner of the heel, a diagonal calk disposed in rear of said recess, and a diagonal calk disposed in front of the recess and having recesses and nail holes in communication therewith, the second-named diagonal calk 15 being of a less depth than the first-named diagonal calk.

In testimony whereof I affix my signature.

LOUIS STEIN.
